UNITED STATES PATENT OFFICE.

BENJAMIN F. BURNS, OF OMAHA, NEBRASKA.

DESIGN FOR A COMBINED ADVERTISING DEVICE AND REVOLVING STAND.

60,083.

Specification for Design.

Patented Dec. 27, 1921.

Application filed April 11, 1921. Serial No. 460,489. Term of patent 3½ years.

To all whom it may concern:

Be it known that I, BENJAMIN F. BURNS, a citizen of the United States, residing at Omaha, in the county of Douglas and State of Nebraska, have invented a new, original, and ornamental Design for a Combined Advertising Device and Revolving Stand, of which the following is a specification, reference being had to the accompanying drawing, forming a part thereof.

Figure 1 is a side view of a combined advertising device and revolving stand, show-

ing my new design. Fig. 2 is a plan view of the same.

I claim:

The ornamental design for a combined advertising device and revolving stand, as shown.

In testimony whereof, I have affixed my signature in presence of two witnesses,

BENJAMIN F. BURNS.

Witnesses:

ARTHUR H. STURGES,
HIRAM A. STURGES.
